Atty.

UNITED STATES PATENT OFFICE.

ELMER RYDER, OF ARGO, ILLINOIS.

END PLATE FOR CUT-OUT VALVES.

Application filed June 25, 1921. Serial No. 480,337.

To all whom it may concern:

Be it known that I, ELMER RYDER, a citizen of the United States, residing at Argo, in the county of Cook and State of Illinois, have invented new and useful Improvements in End Plates for Cut-Out Valves, of which the following is a specification.

This invention relates to improvements in cut-out valves for exhaust pipes of engines for automobiles and other motor vehicles.

In my copending application, Serial No. 424,068, filed November 15, 1920, I have shown and described a cut-out valve structure which may be applied to an exhaust pipe without cutting the same in two. Exhaust pipes of cars of different makes do not have the same diameter, but vary from the smaller size as used on a Ford to the larger sizes as used on other makes of cars.

To enable said cut-out valve fitting to be applied to these exhaust pipes without making it necessary to make different sized fittings, is the object of my present invention, and in accomplishing such object I make the fitting of one standard size and use therewith sets of interchangeable end plates to fit against the pipes at the ends of the fitting and make proper joints at such points. To do this the end plates have their inner edges curved or concaved to conform to the transverse curvature of the various sized pipes, the curvature of said edges being made on radii of the different sized pipes, so that with one set of plates the fitting may be applied to an exhaust pipe of one diameter, and with another set of plates to an exhaust pipe of a different diameter, and so on, there being a set of end plates for each size of exhaust pipe.

In the accompanying drawings—

Fig. 1 shows said valve fitting applied to an exhaust pipe and equipped with end plates made in accordance with my invention and having curved inner edges to conform to the transverse curvature of said pipe, the parts being shown in vertical longitudinal section;

Fig. 2 is a top plan view of the parts shown in Fig. 1;

Fig. 3 is a vertical sectional view taken on line 3—3 of Fig. 1; and

Figs. 4 and 5 are side elevational views of two end plates having the same size lengthwise, but provided with inwardly curved edges on different radii.

In the drawings, 1 indicates an exhaust pipe, and 2 the casing of my said cut-out valve fitting. This casing is shaped somewhat like an elbow and has a single passage extending therethrough. Before the fitting is applied to the pipe 1, a rectilinear opening 3 is cut in the same, and the fitting is applied to said pipe over said opening. The single passage in said casing opens at its inner end into said pipe 1 through said opening 3 and at its outer end through an integral extension 4 with which the casing is provided. To this may be connected a pipe 5, which pipe may lead to a heater in the floor of the car, when the exhaust gases are to be deflected to the heater for warming the interior of the car in cold weather, or the pipe 5 may be open to the atmosphere, when the valve device is used purely for cut-out purposes.

The casing 2 has an integral lug 6 at its base. This lug projects inward and provides a bearing for a valve stem 7, which extends across the passage in the casing and into the exhaust pipe 1 through the opening 3. Secured to the stem 7 are two disk shaped valve members 8 and 9, one in the casing 2 and the other in the exhaust pipe. The valve members 8 and 9 are arranged at right-angles to each other, so that when one is fully opened the other is fully closed. The stem 7 projects out through the casing 2 so that suitable operating mechanism may be connected with it for opening and closing the valves from a point on the dash-board or near the driver's seat.

The base of the casing 2 has the same shape as the opening 3, only larger, and the side edges of the base engage against the pipe 1 along the side edges of said opening, there being a gasket 10 inserted between such parts to make a leak proof joint. The end flanges 11, 11 of the casing are over the end edges of the opening 3 and curved inward or concave on a radius equal to that of an exhaust pipe of the smallest diameter used on a car, so that when the casing is applied to such an exhaust pipe said edges of the end flanges 11, 11 will fit against the exhaust pipe along the corresponding edges of the opening 3 and against the portion of a gasket, such as 10, interposed between such parts. The fitting is clamped to the exhaust pipe by a U-shaped clamp bolt 12 extending around and under the exhaust

pipe and having its ends inserted through ears 13, 13 on opposite sides of the casing, as shown in Figs. 2 and 3.

When applying the fitting to an exhaust pipe of a larger diameter than that just mentioned, the curvature of the edges of the end flanges 11, 11 would not conform to the curvature of such exhaust pipe, and to make a gas tight joint between said end flanges and an exhaust pipe of that diameter, I employ a set of end plates 14, 14. These are secured to the end flanges 11, on the outside thereof, by screws 15, and have their inner edges curved or concave on a radius equal to that of the particular exhaust pipe with which they are used, so as to conform to the outer curvature of the exhaust pipe of that diameter and bear against the interposed portions of the gasket 10. When applying the fitting to an exhaust pipe having a larger or smaller diameter than that mentioned, I secure to the end flanges 11 of the same fitting end plates having their inner edges curved on radii corresponding to the diameters of the pipe with which they are used. For example, in Fig. 4 I have shown an end plate 16 having its inner edge curved to conform to the curvature of an exhaust pipe 17 of a diameter less than that shown in Fig. 3, while in Fig. 5 I have shown an end plate 18 having its inner edge curved on a larger radius so as to conform to the curvature of an exhaust pipe 19 of a diameter greater than either of the ones shown in the preceding figures.

The end plates are interchangeable with the fitting and thus permit the latter to be made one size and usable with exhaust pipes of different sizes. This adapts the fitting to all makes of cars and avoids the necessity and expense of making and handling as many sized fittings as there are different sized exhaust pipes. The advantage of my construction will thus be manifest.

I claim as my invention:

1. The combination with an exhaust pipe having a rectilinear opening in its wall, of a cut-out valve fitting applied to said pipe at said opening, said fitting having an outer casing provided with substantially straight side edges to engage against said pipe along the side edges of said opening and with its ends at the end edges of said opening, the end edges of the casing being curved in-

ward on a radius less than that of said pipe, plates secured to the ends of said casing and having their inner edges curved inward on the same radius as said pipe to conform to the transverse curvature of the pipe and fit against the same adjacent the end edges of said opening, and means for clamping said casing on said pipe.

2. The combination with an exhaust pipe having a rectilinear opening in its wall, of a cut-out valve fitting applied to said pipe at said opening, said fitting having an outer casing provided with substantially straight side edges to engage against said pipe along the side edges of said opening and with its ends at the end edges of said opening, plates secured to the ends of said casing and having their inner edges curved inward on the same radius as said pipe to engage against the same adjacent the end edges of said opening, and means for clamping said casing on said pipe.

3. The combination with an exhaust pipe having an opening in its wall, of a cut-out valve fitting having an outer casing applied to said pipe at said opening and surrounding the same, means for clamping said casing on said pipe, and a plurality of interchangeable sets of plates having their inner edges curved on radii of different diameters and adapted to be attached to said casing for enabling the same to be applied to exhaust pipes of various diameters.

4. A cut-out valve fitting of the character described having an outer casing, said casing having its side edges substantially straight and its end edges curved inward on a predetermined radius to fit against and conform to the transverse curvature of an exhaust pipe of that radius, a plurality of interchangeable sets of end plates adapted to be secured to the ends of said casing, the plates of one set having their inner edges curved inward on a radius different from the plates of any other set and all on radii greater than that of the end edges of said casing to fit against and conform to the transverse curvature of exhaust pipes of different diameters, and means for clamping said casing to exhaust pipes for which the end edges and the plates are provided.

In testimony that I claim the foregoing as my invention, I affix my signature, this 20th day of June, A. D. 1921.

ELMER RYDER.
